(Cl. D21—1)

Fig. 1.

Fig. 2.

Fig. 3.

Fig. 4.

Fig. 1 is a front perspective view of a curtain rod showing my new design;

Fig. 2 is a top plan view thereof;

Fig. 3 is a front elevational view; and

Fig. 4 is an end elevational view thereof.

The dotted lines are intended to indicate indeterminate or indefinite length.

The essential features of the design reside in the bead shown on the rod and bracket portions in combination with the angled brackets all as shown.

I claim:

The ornamental design for a curtain rod substantially as shown and described.
